UNITED STATES PATENT OFFICE

KENNETH HOWIE, OF NORRISTOWN, PENNSYLVANIA, ASSIGNOR TO WILDMAN MFG. CO., OF NORRISTOWN, PENNSYLVANIA, A CORPORATION OF PENNSYLVANIA

FULL FASHIONED KNITTING MACHINE

Application filed November 9, 1929. Serial No. 405,967.

The invention relates to control mechanism for full fashioned knitting machines whereby the operator can quickly advance the machine to the approximate point desired for 5 inspection or manipulation of the knitting elements, and thereafter obtain the exact point desired in the revolution of the machine by turning the machine over by hand, should it not have stopped in the first instance at 10 the precise point desired.

In carrying out the invention, I employ an automatic brake which instantly arrests the machine as a consequence of and when the power is turned off from the driving motor 15 at normal production speeds, together with means for releasing said brake and holding the same released while the machine is being turned slowly over by hand.

I prefer to use an electro-magnetic brake 20 which, as soon as the current is turned off from the driving motor, while running at normal high speed, will quickly arrest the machine, because of the current also having been cut off from said brake at the same 25 time and as a consequence of the power having been turned off from the motor. The machine at this stage in the manipulation, we will suppose, has been brought approximately but not quite to the desired point 30 in its sequence of operations, and for bringing it to the exact point resort is had to hand power operated means, such as the usual hand wheels disposed at various points along the machine front. To enable these hand wheels 35 to be used for turning the machine over, means are provided whereby the brake will be released so that the machine is free to be turned over. This releasing means consists in manually operable devices accessible to the operator at various points along the machine front, which, when operated from any of said points, release the brake so that the exact point may be obtained by operating 45 the machine manually. Further there is provided detent means which will automatically engage the manually operable brake releasing means and hold it in the position to which it has been moved for maintaining the brake in released condition so long as 50 it is desired to turn the machine over slowly

by hand. Provision is made by which, after the operator has turned the machine over by hand to the desired point, he can set the brake by a hand operation so that the machine will be held at said desired point while 55 he is inspecting the work, the knitting elements, or is making repairs or renewal of parts.

Further provision is made by which the manually operable brake controlling means 60 will be restored to its normal or inactive position when the high speed controlling means is set in position for causing the machine to be driven at normal high speed.

In the use of manually operable connections 65 for throwing the power on and off from the motor at high speed, and at the same time releasing and setting the brake respectively as a consequence of said actions, the operator can turn the machine over at high speed to 70 approximately the desired point either by a continuous movement or by a series of short quick steps, or such short quick steps may follow a continuous operation which brings the machine to near the desired point in its 75 operation, the short quick steps resulting in bringing the machine either to the exact point desired or a nearer approach thereto than the continuous movement mentioned, 80 and thereafter the manually operable slow speed can be used, if desired. The short quick steps are obtained by manipulating manually operable devices, such as handles, disposed along the machine front, a number 85 of times, the periods of operation being short, so that the power is thrown on for a short time, then off, and then on again, and so on, the automatic brake arresting the machine instantly each time the power is thrown off, so that the machine advances by the series of 90 short quick movements mentioned above, and the brake of course also acting by a succession of short quick arresting and releasing movements.

This invention is a modification as to some 95 of its features of that disclosed in Letters Patent of the United States granted to me April 15, 1930, Numbers 1,754,680 and 1,754,681 and like in the forms therein disclosed, one object is to relieve the operator 100

of excessive labor of turning the machine over by hand, and at the same time enabling him to bring the machine to the desired point, or approximately to the desired point 5 quickly.

In the drawings:

Figure 1 is a cross sectional view showing enough of the machine as will disclose my invention.

10 Fig. 2 is a plan view.

Fig. 3 is a detail view of manually operable devices for controlling the machine.

Figs. 4, 5 and 6 are views similar to Fig. 3 but with the parts in a different position.

15 Figs. 7, 7a, 8 and 9 are views of details.

Fig. 10 is a plan view of a modification in which the brake is controlled manually through an electric switch.

Fig. 11 shows the neutral position. The 20 brake is applied. Fig. 12 shows the high speed control in neutral position, and handle 44a raised and held to hold the brake released for hand driving.

Fig. 13 shows the high speed control in 25 high speed position with brake released. Fig. 14 shows the high speed control in position for driving at the intermediate speed, the brake being released.

Fig. 15 is a view of a clutch which may be 30 used between the hand drive shaft and the main shaft.

Fig. 16 is a detail view partly in section of the clutch of Fig. 15 associated devices.

In these drawings 6 is the main drive shaft 35 arranged, like in said patents, low down and centrally of the machine. One of the fly wheels is shown at 6b. The cam shaft is shown at 7, driven by gearing 8, 9 from the main shaft. M is the electric motor for driv- 40 ing the machine at normal production speed, i. e., either high or intermediate, the shaft m of this motor having a sprocket wheel 10 which, through a chain 11, drives the sprocket wheel 12 fixed on the main shaft. The cur- 45 rent to the motor is controlled by any suit- able form of switch of standard pattern, and I have indicated conventionally such a switch box at HS for high and intermediate speeds.

This switch is operated by a rack bar 13 and 50 pinion 14, the rack being operated from a rock shaft 15 having an arm 16 fixed thereon to which is connected the rod 17 which forms an extension of the rack 13. This rod is guided through a suitable bracket 18. This 55 control shaft 15 extends along the machine front and is operable by any one of a number of hand levers 19, one for each section or head of the machine distributed along the length of the machine, where they are within 60 convenient reach of the operator from any point along the machine.

When any one of the handles 19 is set in the position shown in Fig. 5, the machine will be driven at normal high speed. When set in 65 position shown in Fig. 6, the machine will be

driven at intermediate speed, and when set at neutral position, Figs. 1 and 3, the power will be cut off from the motor M and at the same time, and as a consequence to this shutting off of power from the motor, the automatic brake will operate to at once stop the machine, the current to the magnet being under the same control means as is the current to the motor. The form of brake that I prefer is electro-magnetic like that disclosed in said Patent No. 1,754,681, and which is so organized that when current is cut off by setting the handle 19 in neutral position, Figs. 1 and 3, the current will be cut off also from magnet 62 of the electro-magnetic brake 70 and the spring 70 will operate segments 66a and 66 and cause the brake band 61 to be set against the brake drum 31 for, at once, stopping the machine. By operating the handle 19 quickly back and forth, the machine can be rapidly advanced by a succession of quick movements to approximately the desired point, so that by thereafter performing the hand driven now to be described, the operator can bring the machine to the exact position desired. 75

The hand drive consists of the usual hand wheels 20 disposed at various points along the machine front on the control shaft 21. There is one of these hand wheels, as usual, for each head or section of the machine. The shaft 21 is connected with the main shaft 6 by chain and sprocket wheels 6a, 6c, 6d, so that by turning any hand wheel the main shaft will be turned over slowly and the machine operated at low speed. 80

We have set forth above that the machine has been brought to rest from its high speed by manipulating any one of the handles 19 to cut off the power and apply the brake. Therefore means are provided for releasing the brake prior to the operation of the hand wheels. This means consists of a rock shaft 42 extending along the machine front having a series of handles 44 attached thereto so that the shaft can be operated from any point along the machine, or in other words, from any station or section of the machine. This shaft 42 is connected by an arm 42a and rod 42b with a bell crank lever 43 which overlies the arm 64 of the electro-magnetic brake. Therefore when any one of the handles 44 is lifted at any of the various stations along the machine, the shaft 42 will be turned and the arm 42a thereon to which rod 42b is connected will operate said rod and the bell crank 43 so that the arm 64 of the brake will be manually depressed to release the brake against the power of the spring 70. The handle 44 and the rock shaft 42 will be maintained in the position just mentioned to hold the brake released by any suitable detent means. As an example of such means, I provide fixed on the shaft 42 an arm 46. This rises at the same time that the handle 44 is 100

lifted and is engaged by a detent 47 which may be in the form of a leaf spring having a detaining projection 48. This detent extends from a block 49 fixed on the shaft 15 before described, said block having also a depending arm 49a arranged parallel with the spring detent and spaced apart therefrom. When any one of the handles 44 is lifted to release the brake to permit the operation of the hand 10 wheels, the arm 46 will get above the detent point 48 and will be maintained thereby in position to hold the brake released, while the slow speed is being operated by hand.

Having reached the exact point at which 15 the machine is desired to set, the operator can restore the brake to hold the machine at this setting by either retracting the detent 47 away from the arm 46 or by exerting sufficient downward pressure on one of the handles 44, 20 the arm 46 may be forced down and thus released from the detent, with the result that the arm 64 of the brake will no longer oppose the force of spring 70 but said spring will be allowed to set the brake, and thus the 25 machine will be held at the desired setting, which, as above described, has been attained by the use of the high speed drive, giving the step by step action to the machine in cooperation with the setting of the automatic brake, 30 the release thereof, and the operation of the hand drive, and if desired, the re-setting of the brake, in the order named.

If it is desired to drive the machine at high speed again, following the inspection or adjustment thereof, or from the position of the parts in Fig. 4, the handle 19 nearest to the operator is pushed by him downwardly. This will swing the arm 49a towards the right and also the detent 47, and thus said detent will 40 be disengaged from the head 46a of the arm 46, and said arm will be free to fall, which will allow the handle 44 also to fall to normal position. The swinging of the arm 49a to the right, i. e., by reason of depressing handle 19, 45 will through the rod 17 close the high speed switch HS, which will supply current to the motor and also to the magnet of the electromagnetic brake for the release thereof, whereupon the high speed running of the machine 50 will have been effected.

If the machine is to be driven at intermediate speed, which speed is embraced within the term "high speed", in a comparative sense, in respect to the low hand speed, the operator 55 will swing the handle 19 up from its neutral position as shown in Fig. 6, instead of down, as in the above description, and analogous actions to those mentioned will be performed.

If it is desired to employ current for energizing the magnet of the brake to release it when any one of the handles 44 is operated, instead of employing the mechanical means, as for instance, the bell crank lever 43, I may employ an electrical switch like that for controlling the auxiliary motor and the brake in

the Patent #1,754,681, April 15, 1930, above mentioned. I refer in this connection to Figs. 10 to 14 inclusive. This switch S would be controlled from the rock shaft 42x like 42 of the first form through arm 49a and rod 17a, operable by any one of the series of handles 44x (like 44 first described) distributed along the machine front, so that when any one of these is lifted, like in the case of handle 44, the switch will be closed, the magnet energized, 70 and the brake will be released. The high speed control shaft 15 in this form has an arm 16 connected with the high speed switch HS by a rod 17. The shaft 15 bears a cam or locking disc 15a provided with a recess 15b. 80 The detent 47x in this instance is adapted to engage a notch 42b in a disc on the shaft 42x, when any one of the handles 44x is lifted, to detain it, the other end of the detent entering the recess 15b. 85

This takes place when the high speed rock shaft 15 with its handles 19 are in neutral position. When the high speed shaft is rocked to drive at high speed, the wall of the recess acts as a cam on the detent and lifts the detent, so that the high speed switch can be closed to release the brake and the handles 44x and the rock shaft 42x can return to normal position.

If the operator desires to set the brake after 95 operating the slow speed drive, by turning the hand wheels, so as to retain the machine in its new setting, he can do so by applying sufficient downward force to any one of the handles 44x and the inclined walls of the 100 notch 42b will cam the detent 47x out of engagement with the said notch and the parts will be in the position shown in Fig. 11. Ordinarily the detent 47x will act as such but its holding action can be overcome by 105 exerting sufficient downward force on handle 44x.

It will be seen from the above that I have provided means whereby the machine by a series of quick step by step actions can be 110 brought approximately to the desired point with the brake set and then by releasing the brake by hand and operating a slow drive connection by hand, the machine can be brought accurately to the desired point. In 115 performing the step by step action the handle 19 is quickly moved back and forth to put on the power and release the brake, and then cut off the power and set the brake.

I may employ a clutch between the hand 120 drive and the main shaft for turning said shaft when the hand wheels are operated to impart the slow forward motion to the said main shaft, said clutch allowing the main shaft to be driven directly by the motor while the hand drive, including the chain and sprocket connection shaft 21 and hand wheels, remain at rest. This will avoid the objections of having the hand wheels and their shaft 21 in rapid rotation, while idling.

and the machine is being driven at normal speed by the motor. Such a clutch may be like that disclosed in my patent above mentioned #1,754,680 and provision can be made in the present machine for reversing the machine with the slow speed drive, like in said patent, consisting of a shiftable key and operating hand lever therefor, to lock the shaft to the clutch body or casing, as indicated in Figs. 15 and 16, in which the clutch members are shown at *a*, the key at *b*, and the hand lever at *c*. The clutch members *a* are rollers mounted in recesses of the sprocket wheel 8. This form of clutch is well known, the purpose being that when the sprocket wheel 8 is driven by the chain the clutch members *a* will drive the shaft 6, but when the shaft 6 is driven by the motor the clutch rollers will slip and the sprocket wheel will remain at rest. As the clutch members *a* are mounted in the sprocket wheel and are so related to the shaft that they grip and turn the shaft only when the sprocket wheel is turned forwardly it is necessary to provide means for connecting the sprocket with the shaft when the said wheel is reversed for driving the shaft 6 backwards and this connecting means consists of the key *b* as stated above, all as in the patent mentioned.

30 Any suitable lock as at *y* may be used for automatically locking the control rod 15 to one of the bearing brackets *y'* against being rotated to start the machine when the reverse drive is to be used. This modification of the apparatus is illustrated in Figs. 15 and 16.

I claim:

1. In combination in a full fashioned knitting machine, power means for driving the machine at normal speed, manually operable control means accessible to the attendant for operation at various points along the machine front for throwing the power on or off, brake means for automatically arresting the machine when the power is thrown off and for releasing the machine when the power is thrown on, a hand drive for the machine operable from various points along the machine front and means for releasing the brake when the hand drive is to be operated, said brake releasing means being manually operable from various points along the machine front, substantially as described.

2. In a full fashioned knitting machine according to claim 1, means for automatically holding the brake released during operation of the hand power drive.

3. In a full fashioned knitting machine according to claim 1, means for automatically holding the brake released during operation of the hand power drive, said holding means being automatically eliminated when the power is delivered to the power operated driving means.

4. A full fashioned knitting machine according to claim 1, having means for auto-

matically holding the brake released during operation of the hand power drive, said holding means being releasable by the operator for setting the brake when the hand drive brings the machine to the desired point. 70

5. In a full fashioned knitting machine, a normal speed power drive, manually operable control means accessible to the operator at various points along the machine front for supplying power to or cutting it off from said normal drive, means for operating the machine by hand accessible to the operator at various points along the machine front, a brake operating automatically for arresting the machine when power is cut off from the normal speed drive, and releasing the machine when power is supplied to said normal speed drive hand controlled means for releasing the brake accessible to the operator at various points along the machine, means for automatically holding the brake released while the hand power means is operated to drive the machine, said holding means being released automatically by the operation of the manually operable control means when the latter is set in position for operation of the normal speed drive. 80 85 90

6. In a full fashioned knitting machine, a main shaft located centrally of the lower part thereof, a shaft at the upper front part of the machine, with means for driving it by hand from various points along the machine front, a driving connection between said upper shaft and the main shaft for driving the latter from the former, power operated means for driving the main shaft, a brake, means for throwing the brake on automatically when the power is thrown off for stopping the machine and for releasing the brake automatically when power to drive the machine is thrown on, control means accessible to the attendant at various points along the machine for supplying power to or cutting it off from the power drive, and manually operable means accessible to the attendant at various points along the machine for releasing the brake to enable the machine to be driven by hand, substantially as described. 100 105 110

7. In combination in a full fashioned knitting machine, a power operated drive, manually operable control means for the power drive accessible to the attendant at various points along the machine, a hand drive accessible to the attendant for operation at various points along the machine front, a brake for automatically arresting or releasing the machine according to whether the control means is set to cut off or deliver power to the power driving means, manually operable means accessible at various points along the machine for releasing the brake so that the machine may be driven by hand, a catch for holding the brake released, said catch being operable from the power drive control means to restore control of the brake to said power 115 120 125

drive control means or to hold the manual brake releasing means, substantially as described.

8. In combination in a full fashioned knitting machine, a main shaft disposed at the lower central part of the machine, power operated means for driving said shaft, automatic brake means to arrest the machine when the power is cut off, a control rod extending along the upper front part of the machine for controlling the power to the power means and for also controlling the brake, a shaft extending along the front of the machine having hand wheels at various points, a connection between said hand wheel shaft and the main shaft for driving the machine by hand, a manually operable rock shaft disposed along the front of the machine with means controlled thereby for releasing the brake after said brake has set itself automatically as a consequence of operating the power control rod to throw off the power, so that the machine then may be turned over by the hand wheels.

25 9. In a full fashioned knitting machine according to claim 8, said rock shaft having handles at said various points, an arm mounted on the rock shaft, a detent to engage said arm when the shaft is turned to release the brake and means whereby said detent releases the said arm automatically when the machine is again started under power.

10. In a full fashioned knitting machine 35 according to claim 8, said rock shaft having handles at said various points, an arm mounted on the rock shaft, a detent to engage said arm when the shaft is turned to release the brake and means whereby said detent releases the said arm automatically when the machine is again started under power, said power control rod being in the form of a rock shaft and said detent being moved to its holding position and its released position by the 45 turning of said rock shaft.

11. Apparatus according to claim 1, in which the brake is set automatically by a spring, and means acting in opposition to said spring under control of said manually 50 operable brake releasing means, substantially as described.

12. Apparatus according to claim 1, in which the brake is set automatically by a spring, and mechanical means operated by 55 the said manually operable brake releasing means, neutralizes said spring for the release of the brake, substantially as described.

13. Apparatus according to claim 1, in which the power means is an electric motor 60 and the brake is electro-magnetic and the control means includes an electric switch for supplying current to and removing it from the motor, and said manually operable brake releasing means includes an electric switch for supplying current to and 65

cutting it off from the electro-magnet of the brake, substantially as described.

14. Apparatus according to claim 1, in which the power means is an electric motor, the brake is electro-magnetic and is set in 70 braking position by a spring, and the manually operable brake releasing means includes a mechanical device for opposing the spring, substantially as described.

15. A full fashioned knitting machine 75 comprising power means for driving the machine at normal speed, hand operated driving means, a brake which is set automatically when the power is off, and manually operable means for releasing the brake when the machine is to be driven by hand power.

16. Apparatus according to claim 15, having a detent to hold the brake released while the machine is driven by hand.

17. Apparatus according to claim 15, in 85 which a detent automatically acts to hold the brake when released, and means for releasing the detent automatically when the machine is restored to operation by power.

18. A full fashioned knitting machine 90 comprising power means for driving it at normal speed, hand operated driving means, a brake which is set automatically when the power is off, manually operable means for releasing the brake when the machine is to 95 be driven by hand power, means for automatically holding the brake when released by said manually operable means, said holding means being automatically withdrawn from action when power operation is resumed, and being also releasable manually 100 from various points along the machine front.

19. In combination in a full fashioned knitting machine, means for operating the machine at normal and slow speeds, automatic brake means which arrests the machine when power is thrown off at normal speed and releases the machine when power is thrown on for normal speed, manually controlled means accessible to the operator at 105 various points along the machine for controlling the throwing on and off of power from any of said points, manually controlled means accessible to the operator at various points along the machine for releasing the 110 brake preparatory to operating the machine at slow speed, said last mentioned brake releasing means being automatically eliminated when the first mentioned manually controlled means is operated to drive the machine at 115 normal speed.

In testimony whereof, I affix my signature.
KENNETH HOWIE.
